UNITED STATES PATENT OFFICE

JOHN C. HIGGINS, OF SAN DIEGO, CALIFORNIA

AUTOMATIC WATER-HEATER CONTROL-VALVE APPARATUS

Application filed February 28, 1928. Serial No. 257,685.

My invention relates to automatic heater control valves and the objects of my invention are: First, to provide a valve of this class which is adapted for any use in which the passage of one fluid is desired to automatically control the passage of a second fluid; second, to provide a valve of this class which is especially adapted for automatic water heaters using gas fuel; third, to provide a valve of this class which is a double valve consisting of a water valve and gas valve combined in a single unit and in which the water passing through its valve portion operates the gas valve which permits the passage of the correct amount of gas necessary for heating the water to the desired temperature, thus within limit, the temperature of the water after leaving the automatic heater is approximately constant regardless of the volume; fourth, to provide a valve of this class in which a water valve and gas valve are mounted in the same housing and on the same axis with a partition extending between the water valve and the gas valve and in which a stem integral with the water valve extends through a packing gland mounted in said partition for operating said gas valve; fifth, to provide a valve of this class in which the fluid in one valve portion cannot pass into the other valve portion; sixth, to provide a valve of this class which requires no further adjustment when once installed; and seventh, to provide a valve of this class which is compact, efficient in its action, durable, which is provided with a minimum of moving parts and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application in which:

Figure 1 is a longitudinal sectional view of my valve apparatus through 1—1 of Fig. 2; Fig. 2 is a transverse sectional view there-

of through 2—2 of Fig. 1; Fig. 3 is a transverse sectional view thereof through 3—3 of Fig. 1; Fig. 4 is a longitudinal sectional view thereof through 4—4 of Fig. 5; Fig. 5 is a transverse sectional view thereof through 5—5 of Fig. 4; and Fig. 6 is another transverse sectional view thereof through 6—6 of Fig. 4.

Similar characters of reference refer to similar parts and portions throughout the several views of the drawings.

Valve housing 1, water valve cap and inlet 2, water valve plunger 3, packing gland 4, gas valve plunger 5, gas valve cap 6, and spring 7, constitute the principal parts and portions of my automatic heater control valve.

The valve housing 1 is substantially cylindrical in shape and is provided with an enlarged chamber portion at its lower extremity which forms the water valve chamber 1^a. A hollow boss portion 1^b extends from the side of the chamber 1^a forming the water outlet passage. The lower extremity of the water valve chamber 1^a is closed by a water valve cap 2. The cap 2 is provided with a central opening 2^a which serves as the water inlet passage. A valve plunger 3 fits snugly within the chamber 1^a and is adapted to reciprocate therein. A depressed portion 1^c extends along the side wall of the chamber 1^a and communicates with the outlet passage 1^b, thus providing a bypass around the valve 3, as shown best in Figs. 1 and 6 of the drawings.

The chamber 1^a is closed across its upper portion forming a partition 1^d which is provided with a small central opening therein. A water valve stem 3^a is centered on the water valve 3 and extends upwardly through the opening provided in the partition 1^d. An internally threaded boss portion 1^e concentric with the stem 3^a depends from the partition 1^d. A packing gland 4 fits around the stem 3^a and is adapted to screw within the boss portion 1^e forcing the packing tightly against the stem 3^a and preventing any leakage of fluid into and out of the chamber 1^a, yet permitting the reciprocal movement of the water valve. A sleeve member 3^b integral with the water valve 3 and in the form of an

annular ridge concentric with the water valve stem 3^a fits snugly around the outside of the boss portion 1^e and prevents grit or the like from coming in contact with the valve stem and packing gland, thus preventing excessive wear.

The unenlarged portion of the valve 1 is provided with a pair of chambers 1^f and 1^g separated by a perforated partition 1^h. The 10 chambers 1^f and 1^g form the gas valve chamber of my automatic water heater valve apparatus. The lower chamber 1^f is provided with an extended passage 1^j which forms the gas intake. An opening 1^k which communicates with the pilot burner of the automatic heater, not shown, is provided in the chamber 1^f. The upper gas chamber 1^g is provided with a passage 1^m extending therefrom which forms the gas outlet passage. An opening 1ⁿ 15 similar to the opening 1^k is provided in the chamber 1^g. Said opening is manually closed with a plug. Should it be desired to use the passage 1^j as the outlet and the passage 1^m as the inlet, the plug is placed in the lower 20 opening 1^k and the opening 1ⁿ is connected to the pilot burner.

It is preferred to have the water outlet passage 1^b, the gas inlet passage 1^j, and the gas outlet passage 1^m terminate in the same plane 30 thus facilitating installation and manufacture. This is accomplished by making the passages integral with the housing 1 and conducting the passages 1^j and 1^m downwardly along the sides thereof until reaching the plane of the 35 water outlet passage 1^b. The passages then extend outwardly and are provided with suitable coupling means.

A gas valve plunger 5 is adapted to rest upon the perforated partition 1^h, said gas 40 valve plunger is provided with a central stem 5^a which extends downwardly, and engages the upper portion of the stem 3^a of the water valve 3, as shown best in Figs. 1 and 4 of the drawings. The upper portion of the stem 5^a 45 extends into a centered socket 6^a provided in the cap member 6. A spring 7 extends between the gas valve cap 6 and the upper surface of the gas valve plunger 5. Said spring tends to hold the gas valve plunger tight 50 against the perforated partition 1^h. The under surface of the gas valve plunger 5 is provided with suitable soft material 5^b to form an efficient seal against the passage of gas when 55 the valve is closed.

The operation of my automatic heater valve is as follows:

The passage 1^b is connected by suitable pipes to the cold water intake of the automatic heater; the water inlet 2^a is connected to the 60 source of water supply; the gas inlet 1^j is connected to the source of gas supply; and the gas outlet 1^m is connected to the gas burner of the automatic heater. The connecting parts and portions are not claimed as a part of my 65 invention and hence are not shown. When a

faucet which is in connection with the hot water heater is turned on, the pressure in the passage 1^b is reduced thus permitting the pressure from the source of water supply to lift the water valve. The movement of the 70 water valve 3 causes the gas valve plunger 5 to open and permit the flow of gas therethrough. If a faucet connected through the heater with the outlet passage 1^b is opened full force, the water valve rises to its full 75 height and permits a maximum flow of gas; conversely, when only a small amount of water is passing through the passage 1^b, the water valve plunger 3 is only slightly open and only a small amount of gas is allowed to pass. Thus, it is possible to heat the water to a given temperature and yet permit a wide 80 fluctuation in the amount of water heated for any given time.

It will be noted that although my device is 85 described as an automatic control valve for automatic heaters, it is obvious that my valve can be used wherever it is desired to regulate the flow of one fluid relative to another.

It is obvious from the construction as illustrated in the drawings and described in the foregoing specification that there is provided an automatic heater control valve as aimed at and set forth in the objects of the invention and though I have shown and described a particular construction, combination and arrangement of parts and portions I do not wish to be limited to this particular construction, combination and arrangement of parts and portions but desire to include in the scope of 95 my invention the construction, combination and arrangement substantially as set forth in the appended claims.

Having thus described my invention, what I claim as new and desire to secure by Letters 105 Patent is:

1. In a valve apparatus of the class described, a housing, a pair of superposed chambers formed therein and separated by a single integral partition, a fluid valve plunger mounted in the one of said chambers, a gas valve plunger mounted in the other of said chambers, and a separable stem extending between said fluid valve plunger and said gas 110 valve plunger for operating said gas valve plunger simultaneously with said fluid valve plunger.

2. In a valve apparatus of the class described, a valve chamber provided with a depression in the side wall thereof, inlet and outlet passages communicating with said chamber and depression, a valve plunger slidably mounted in said chamber, a second valve chamber mounted in superposed relation to said first mentioned chamber, a valve plunger mounted in said second chamber, a stem for each of said plungers with their inner ends in loose abutment simultaneously operating said first and second mentioned valve plungers.

3. In a valve apparatus of the class de-

scribed, a valve chamber, inlet and outlet passageways communicating therewith, a valve plunger mounted therein, a bypass around said valve plunger connecting said outlet and 5 said inlet, a second valve chamber mounted in superposed relation to said first mentioned chamber, a valve plunger mounted in said second chamber, a stem for each of said plungers with their inner ends in loose abut- 10 ment simultaneously operating said first and second mentioned valve plungers.

4. In a valve of the class described, a valve chamber, inlet and outlet passageways communicating with said chamber, a valve plunger 15 slidably mounted in said chamber, a second valve member, superposed on and integral with said first chamber, a perforated partition dividing said second valve chamber, a valve plunger mounted in said second valve 20 chamber adapted to seat on said partition, inlet and outlet passageways intersecting said second valve chamber on opposite sides of said partition, means connecting said second mentioned valve plunger with said first mentioned valve plunger for simultaneously 25 operating said valve plungers.

5. In a valve of the class described, a valve chamber, inlet and outlet passageways communicating therewith, a valve plunger mounted 30 therein, a bypass around said valve plunger connecting said outlet and said inlet, a second valve chamber, superposed on and integral with said first chamber, a perforated partition dividing said second valve chamber, a 35 valve plunger mounted in said valve chamber adapted to seat on said partition, inlet and outlet passageways intersecting said second valve chamber on opposite sides of said partition, means connecting said second mentioned 40 valve plunger with said first mentioned valve plunger for simultaneously operating said valve plungers.

6. In a valve of the class described, a single housing, a pair of superposed chambers 45 therein, a single partition separating said chambers, a stem extending through said partition and slidably relative thereto, a single packing gland in said housing forming a fluid tight joint between said stem and said 50 partition, a valve plunger mounted in the one of said chambers and secured to said stem, a second valve plunger mounted in the other of said valve chambers engageable with said stem.

55 7. In a valve of the class described, a single housing, a pair of superposed chambers therein, a single partition separating said chambers, a stem extending through said partition and slidably relative thereto, a single packing 60 gland in said housing forming a fluid tight joint between said stem and said partition, a valve plunger mounted in the one of said chambers and secured to said stem, a perforated partition provided in the other of said 65 chambers, a valve plunger adapted to seat

upon said partition and engageable with said stem.

8. In a valve of the class described, a single housing, a pair of superposed chambers therein, a single partition separating said chambers, a stem extending through said partition and slidably relative thereto, a packing gland in said housing forming a fluid tight joint between said stem and said partition, a valve plunger mounted in the one of said chambers 70 and secured to said stem, a perforated partition provided in the other of said chambers, a valve plunger adapted to seat upon said diaphragm and engageable with said stem, inlet and outlet passageways communicating with said first mentioned chamber, a bypass extending around said first mentioned valve plunger and connecting said inlet and outlet passageways. 75

8. In a valve of the class described, a single housing, a pair of superposed chambers therein, a single partition separating said chambers, a stem extending through said partition and slidably relative thereto, a packing gland in said housing forming a fluid tight joint between said stem and said partition, a valve plunger mounted in the one of said chambers 80 and secured to said stem, a perforated partition provided in the other of said chambers, a valve plunger adapted to seat upon said partition and engageable with said stem, inlet and outlet passageways communicating with said first mentioned chamber, a bypass extending around said first mentioned valve plunger and connecting said inlet and outlet passageways. 85

9. In a valve of the class described, a single housing, a pair of superposed chambers therein, a single partition separating said chambers, a stem extending through said partition and slidably relative thereto, a packing gland in said housing forming a fluid tight joint between said stem and said partition, a valve plunger mounted in the one of said chambers 90 and secured to said stem, a perforated partition provided in the other of said chambers, a valve plunger adapted to seat upon said partition and engageable with said stem, inlet and outlet passageways communicating with said first mentioned chamber, a bypass extending around said first mentioned valve plunger and connecting said inlet and outlet passageways, other inlet and outlet passages 95 intersecting said second mentioned chamber on either side of said partition. 100

In testimony whereof, I have hereunto set my hand at San Diego, California, this 16th day of February, 1928.

JOHN C. HIGGINS.
